US0D1085000S

(12) **United States Design Patent** (10) **Patent No.:** **US D1,085,000 S**
(45) **Date of Patent:** **** Jul. 22, 2025**

(54) **WIRELESS CHARGER**

(71) Applicant: **Shenzhen Mgctech Co., Ltd.**,
Shenzhen (CN)

(72) Inventor: **Jiedan Li**, Shenzhen (CN)

(**) Term: **15 Years**

(21) Appl. No.: **29/933,430**

(22) Filed: **Mar. 19, 2024**

(30) **Foreign Application Priority Data**

Feb. 1, 2024 (CN) 202430070740.7

(51) **LOC (15) Cl.** **13-02**

(52) **U.S. Cl.**

USPC **D13/108**

(58) **Field of Classification Search**

USPC D13/103, 107, 108, 118, 119, 183, 199;
D14/447, 251, 252, 253

CPC H02J 7/0044; H02J 7/0045; H04B 1/3883

(57) **CLAIM**

The ornamental design for a wireless charger, as shown and described.

DESCRIPTION

FIG. 1 is a perspective view of the wireless charger showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof; and,

FIG. 7 is a bottom plan view of thereof.

The broken lines depict portions of the wireless charger that form no part of the claimed design.

1 Claim, 7 Drawing Sheets
